US0D1053543S

(12) **United States Design Patent** (10) Patent No.: **US D1,053,543 S**
(45) Date of Patent: ** Dec. 10, 2024

(54) **SHOE**

(71) Applicant: **Jiangxi Baolong Outdoor Products Co., Ltd.**, Shangrao (CN)

(72) Inventor: **Hui Huang**, Shangrao (CN)

(73) Assignee: **Jiangxi Baolong Outdoor Products Co., Ltd.**, Shangrao (CN)

(**) Term: **15 Years**

(21) Appl. No.: **29/947,844**

(22) Filed: **Jun. 18, 2024**

(51) LOC (14) Cl. **02-04**

(52) U.S. Cl.

USPC **D2/969**; D2/910

(58) **Field of Classification Search**

USPC D2/902–912, 947, 969–978

(57) **CLAIM**

The ornamental design for a shoe, as shown and described.

DESCRIPTION

FIG. 1 is a rear, left and top perspective view of a shoe, showing my new design;

FIG. 2 is a left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines shown in the drawings illustrate portions of the shoe that form no part of the claimed design.

1 Claim, 8 Drawing Sheets
